A. K. DELLAUROE AND ONE-HALF TO EMMA HULL, BOTH OF LOS ANGELES,
CALIFORNIA.

ENVELOP-HOLDING ATTACHMENT FOR PRINTING-PRESS PLATENS.

1,401,174.

Specification of Letters Patent. Patented Dec. 27, 1921.

Application filed January 10, 1921. Serial No. 436,095.

To all whom it may concern:

Be it known that I, CHARLES HUGH MARTIN, a citizen of the United States, residing at Los Angeles, in the county of Los Angeles and State of California, have invented a new and useful Envelop-Holding Attachment for Printing-Press Platens, of which the following is a specification.

This invention is more particularly adapted for use on platen presses in connection with the Miller pneumatic feeder when used in connection with the envelop separator for printing presses, described in my application, Serial No. 406,812, filed 15 August 30, 1920, and in which a tappet in the form of a slight protuberance is arranged to project over one edge of a stack of envelopes and is adapted to intercept such of the envelopes as are not in direct touch with 20 the pneumatic lifting means.

In presses provided with the devices above referred to, envelopes are fed one by one upon the platen of the press by means of a rack, and are shifted endwise laterally 25 upon the platen to a gage bar and there held until printed; but after the envelop has been placed upon the platen, the rack raises slightly and passes up over the envelop; after which the printing is done and the envelop 30 is removed from the platen. It is a common occurrence for a "window" envelop or an envelop delivered to the platen in a crumpled or bent form, to be dragged by the rack as it returns over the envelop, and consequently the envelop is displaced from 35 the position in which it should be when printed, so that the impression is out of place; or, more likely the rack on return, will drag the envelop back, and so crumple 40 and displace it as to clog the press and necessitate stopping the same, to unclog it thus causing great waste of time as well as loss by destruction of envelopes.

An object of this invention is to provide 45 means which may be easily attached to the platen pad of the press in proper position and when so attached will receive the envelop as it is placed on the platen and will hold the same against displacement by said 50 rack and yet allow the envelop to be shifted by the mechanism provided therefor in devices such as the Miller pneumatic envelop feeder.

Simplicity, cheapness and ease of apply-

ing and removing are other objects of the 55 invention.

Further objects, advantages and features of invention may appear from the accompanying drawing, the subjoined detail description and the appended claims. 60

The invention may be applied in various forms.

The accompanying drawing illustrates the invention in the forms at present deemed most desirable. 65

Figure 1 is a perspective view of a preferred form of the invention applied to the platen of a printing press; an envelop is shown clamped in position thereby and grasped by a "bird" for removal. 70

Fig. 2 is a perspective view of one of the clips detached.

Fig. 3 is an enlarged plan view of one of the clips.

Fig. 4 is an elevation of one of the clips 75 in section on line $\alpha\beta$, Fig. 3.

Fig. 5 is an edge elevation of a clip of another construction detached.

Fig. 6 is a fragmental view on enlarged scale, of one of the clips in use holding an 80 envelop on a platen, fragments of which are shown in section.

Fig. 7 is a plan of another form of clip.

The clamp is made up of two clips 1, 2, which operate on the same principle, but 85 are constructed as rights and lefts.

Each clip is shown in the drawings as made of a strip of resilient material, preferably spring steel; and comprises a body 3 having at one end a lip 4 to fit against 90 the near edge of the platen and adapted to be clamped onto the platen by the usual pad clamp α . Said body 3 extends from the lip 4, to rest on the platen pad. It is preferably provided with spring limbs 5, 95 6, 7, 8, the limbs 5, 6 and 8 being parallel to each other and the limb 7 being transverse thereto and forming a lateral extension the tip of which is a runner. Limb 7 is a spring connecting limbs 6 and 8 to 100 comply with the resilient requirements of the envelop clamp. The limb 8 terminates in front and back bends 9, 10 formed by turning up the ends of limb 8. The strip forming the clip may be constructed of one 105 or more pieces, the limb 5 being an extension of the body 3, and the limb 6 being connected thereto at the end, farthest from the

lip, in any suitable manner as by rivets 6' in Figs. 1-4, the return bend 5 in Fig. 5 or the end turn 6 in Fig. 7. The limb 8 is turned up at its ends so as to allow an envelop 11 to pass freely under the guide from either direction, and the transverse limb 7 is preferably bent up at its root close to the limb 6 to hold the runner at an elevation to accommodate the envelops 11.

10 In practice the clips are applied as rights and lefts in suitable position on the platen pad 12 equidistant from the center line of envelop delivery, and are secured to the platen pad by the pad clamp *a*, at a distance apart greater than the length of the envelops to be printed, but close enough to each other to extend over the envelops sufficiently to compensate for shortening of the envelop by crumpling or bending. The 20 ends of the guides are both turned up from the platen-pad engaging face of the guide so as to allow the envelop to pass freely into the clamping position without interference by the edges of the window slot or 25 orifice 13.

The construction and arrangement of the guide, the tongue, and the connection between the tongue and guide is such that although the envelop is securely held upon the 30 platen, it may be shifted endwise or edgewise; but the pressure of the guides and tongues is sufficient to hold the envelop down below the level of the rack, not shown, which passes down and back over the face of the 35 platen.

By the construction shown, window envelops, that is to say, envelops having an orifice 13 cut therein to expose the written address on the latter when the same is in 40 closed, are caught by the guides 9 and 10 and are firmly held down while the envelop is being shifted on the platen pad, edgewise or endwise.

The guides 8 are long enough to extend 45 clear across the windows, and the up-turned ends 9 and 10 do not allow the guides to catch on the margins of the window.

By providing the pair of clips provided with resiliently mounted extensions 7, 8 extending toward each other and adapted to engage and hold an envelop toward the platen the envelops may be printed and delivered from the press without the losses hereinbefore referred to.

55 I claim.

1. A pair of clips for a printing press platen adapted to be fastened to the platen and provided with resiliently mounted lateral extensions extending toward each other 60 and adapted to engage and hold an envelop against the platen substantially as and for the purpose set forth.

2. An envelop holding attachment for

65 platen presses comprising a body adapted to be fastened to a platen; and resilient limbs connected to said body and forming a lateral extension from the body to hold an envelop between its tip and against the platen.

3. An envelop clamp for use on printing 70 press platens comprising a spring limb having a tip adapted to extend over an envelop to be printed and to hold such envelop between it and against the platen; and means to connect said spring limb to the platen.

4. An envelop clamp for use on printing 75 press platens comprising a spring limb having a tip adapted to extend over an envelop to be printed and to accommodate such envelop between it and the platen and to hold such envelop against the platen.

5. An envelop clamp for use on printing 80 press platens comprising a body, a spring limb connected to and extending laterally from said body and having a runner adapted to extend over an envelop to be printed and to hold such envelop between it and against the platen; and means to connect said lateral limb to the body; said runner extending transversely to the lateral link and turned 85 up at its ends.

6. An envelop clamp for use on printing 90 press platens comprising spring limbs connected together, one of said limbs being transverse to another and having a tip adapted to extend over an envelop to be 95 printed and to hold such envelop between it and against the platen; and means to connect said spring limb to the platen.

7. An envelop holding attachment for 100 platen presses comprising a body adapted to be fastened to a platen, and a resilient limb supported by the body and forming a projection at one edge of the body and adapted to receive the end of an envelop between its tip and the platen.

8. The combination with a printing press 105 platen of a pair of right and left clips having lateral resilient guides to receive the ends of envelops and hold them against the platen.

9. A pair of clips for a printing press 110 adapted to be fastened to the platen, each clip comprising a body, a resilient limb attached at one end to said body and lying in parallel relation thereto, a lateral extension 115 on said limb, and members extending from the end of said extension in parallel relation to said body, said members being turned up at their ends.

In testimony whereof, I have hereunto set 120 my hand at Los Angeles, California, this 31st day of December, 1920.

CHARLES H. MARTIN.
